B. E. MEACHAM

OVEN DOOR HINGE

Filed April 1, 1925

FIG. 1.

FIG. 2.

FIG. 3.

FIG. 4.

B. E. Meacham,
By A. Patterson Son

Attorneys

UNITED STATES PATENT OFFICE.

BENJAMIN E. MEACHAM, OF LORAIN, OHIO, ASSIGNOR TO AMERICAN STOVE COMPANY, OF ST. LOUIS, MISSOURI, A CORPORATION OF NEW JERSEY.

OVEN-DOOR HINGE.

Application filed April 1, 1925. Serial No. 19,908.

To all whom it may concern:

Be it known that I, BENJAMIN E. MEACHAM, a citizen of the United States, residing at Lorain, in the county of Lorain 5 and State of Ohio, have invented certain new and useful Improvements in Oven-Door Hinges, of which the following is a specification, reference being had therein to the accompanying drawing.

10 This invention relates to improvements in oven door hinges, and the primary purpose of the present invention is to construct the hinges so that they are entirely concealed when the oven door is closed.

15 A further object of the present invention is to locate an oven door hanger or hinge at the inner side of the frame of the oven, whereby the same when closed is completely concealed.

20 Another object of the present invention is to provide a hinge or supporting member for an oven door, which when the door is closed it is wholly concealed, and when the door is open only one end of the support 25 or hinge is visible.

A further object of the present invention is to make a hinge for oven doors which is essentially L-shaped, the long leg of the L within the frame of the oven or stove, and 30 the short leg of the support or hinge hinged to the door, whereby the said hinge or supporting member is wholly concealed when the door is closed.

A further object of the present invention 35 is to provide a hinge or supporting member substantially L-shaped, with the long leg of the L pivoted to the inner sides of the oven or stove, and the short leg passing through an opening in the wall or frame of 40 the stove and pivoted to the oven door, and a spring located between the long leg of the hanger and the frame of the stove.

Another object of the present invention is to locate the supporting or hinged member 45 with its spring in a flue of the oven, whereby the spring is not subjected to the extreme heat of the oven and thereby the temper of the spring is not destroyed.

Further objects of the present invention

will appear from the following description and disclosure.

In the accompanying drawings,

Figure 1 is a front elevation showing a two-door oven, the hinges or supports for the doors shown in dotted lines.

Fig. 2 is a sectional view on the line 2—2 of Figure 1, the upper door being shown open and the lower door closed.

Fig. 3 is a horizontal sectional view on the line 3—3 of Figure 2.

Fig. 4 is a front elevation partly in section of one corner of the door.

In the construction herein shown there are no parts of the hinge or support that is at all visible when the oven door is closed, thus making the front of the stove free from the usual type of external hinges and fastening devices therefor, which are unsightly and necessarily more expensive to manufacture than the hinges of this application.

In the drawings, 1 is a frame for the oven door opening 2, the said opening being closed by a suitably shaped door 3. In the form of door here shown, the lower corners 4 somewhat extend beyond the door, but I desire it to be understood that the door may be of the same shape entirely around its edge without departing from the idea here disclosed. Also the door here shown has its edge made U-shaped, as shown at 5, with an internal portion 6, which latter may or may not be enameled.

The door-frame 1 is made sufficiently large to extend over a vertical flue 7, for a purpose to be presently explained.

In carrying forward my present improvement, I provide a supporting member 8 that has its upper end hinged at 9, to a suitable extension 10 from the frame 1 of the oven-door opening 2. This member 8, as here shown, extends downwardly and has its lower end 9' pivotally connected at 10' with a lug or lugs 11, which extend inward from the U-shaped part 5 of the door. It will be understood, of course, that there is a member 8 for each corner of the door. In the form here shown, the member 8 preferably

extends upward within the flue 7, though I desire it to be understood that it may extend downward in the said flue without departing from the scope of the present invention, since the flue 7 extends from top to bottom of the oven.

For the purpose of easing the door in its downward movement, I provide a suitable spring 12, which is coiled and located between the member 8 and the frame 1. This spring is compressed when the door is opened, whereby it opens against some pressure of the spring, and the spring serves to hold the door closed.

18 The lower edge 13 of the U-shaped part 5 engages the lower portion 9' when the door is open, whereby it is held in a horizontal position and is not permitted to swing beyond that position. It will be understood 20 that the edge 13 regulates the amount of outward movement that the door may be permitted, and, therefore, the angle of the door when opened is regulated by the engagement of the part 13 with the under edge 25 of the part 9' of the hinge or supporting member 8.

Preferably the lower end 9' of the hinge member 8 extends inward at an angle to the part 8, and as shown, the part 8 is thereby preferably made substantially L-shaped in contour.

When the door is closed the U-shaped part 5 is held against the frame 1. Hence in opening the door, the lower edge 13 slides on the frame, and for the purpose of facilitating this sliding movement, I provide the door-frame with a downwardly extending rib 14, with which the edge 13 of the U-shaped part engages when the door is moved to open position.

I desire it to be understood that the frame of the oven A or stove, may be made in any desired form, but preferably it has at opposite sides of the door frames vertically arranged flues 7, in which flues the hangers 8 are located for the purpose of protecting the spring 12 and the hangers from the heat within the oven, as will be readily understood. In that manner the springs are not subjected to the intense heat of the oven and the temper of the spring is not destroyed.

I also desire it to be understood that the oven and the surrounding frame, and the shape of the door may be substantially of any desired construction without departing from the invention herein disclosed.

I also desire it to be understood that the specific construction of the invention here disclosed may be varied so long as the change is within the spirit and scope of the appended claims.

Having thus described my invention, what I claim and desire to secure by Letters Patent is:

1. A door hinge comprising a door, a door frame, a member at the inner side of the frame having one end connected with the frame and the opposite end connected with the door and a spring connecting the frame and said member, the spring acting to hold the door closed. 70

2. A door hinge comprising a door, a door frame, a member having one end pivoted to the frame and its opposite end pivoted to the door, and an expanding spring between the member and the said frame. 75

3. A door hinge comprising a door frame, a door, a member extending within the frame and having one end pivotally connected with the said frame, the opposite end pivotally connected with the door above its lower edge, whereby the lower edge of the door engages the frame when the door is opened. 80

4. A door hinge comprising a door frame, a door, a member located inside of the said door having one end pivotally connected with the frame and its opposite end connected with the lower part of the door above its lower edge, said frame having a vertical rib for the lower edge of the door to slide upon as the door is opened. 90

5. A stove door hinge comprising a door frame, the stove having a vertical flue located behind the said frame, a vertical member in the said flue, said member having its upper end pivotally connected with the door and its lower end pivotally connected with the lower part of the door, and a spring located between the said member and the door frame. 95

6. An oven door hinge comprising an oven, a door frame, a flue located at the inner side of the door frame, a member located at the inner side of the frame and having its upper end pivotally connected to a wall of the said flue and its lower end pivotally connected with the door, for the purpose described. 105

7. An oven door hinge comprising an oven having a vertical flue, a door frame located at the outer face of the said flue and forming an outer wall therefor, of a vertical member in the said flue, one end of the member pivotally connected with the wall of the oven flue and its opposite end pivotally connected with the door, and a hinge located between the said member and the wall of the flue. 115

8. An oven door hinge comprising an oven, a door-frame, a door located against the outer face of the said frame, a hinged member having one of its end pivotally connected to the inner side of the door-frame and its lower end extending outward and pivotally connected with the door, and means for holding the door closed. 125

9. An oven door hinge comprising a door frame, a door, an L-shaped member having 130

one leg of the L pivotally connected to the inside of the door frame and the other leg of the L-shaped member extending outward and pivotally connected to the said door.

- 5 10. A concealed oven door hinge comprising a door frame, a door located at the outer face of the said door frame, and a member located wholly within the door frame when

the door is closed, said member having one end pivotally connected with the said frame 10 and its opposite end pivotally connected with the said door, and means for holding the door normally closed.

In testimony whereof I hereunto affix my signature.

BENJAMIN E. MEACHAM.
